WELL PUMP

Herbert A. Schmidt, Whittier, Calif., assignor of
one-half to James V. Keith, Los Angeles,
Calif.

Application September 8, 1936, Serial No. 99,750

15 Claims. (Cl. 103—190)

This invention relates to pumping apparatus and relates more particularly to well pumps. A general object of this invention is to provide a practical and very efficient double acting well pump.

Another object of this invention is to provide a pump for use in oil wells, etc. that is operable to alternately discharge charges of liquid and gas into the oil string.

Another object of this invention is to provide a deep well pump that assures the efficient recovery of the liquid or oil from the well by discharging a charge of gas into the oil string following each oil elevating stroke, which gas materially assists in raising the oil to the surface.

Another object of this invention is to provide a double acting pump of the character mentioned that is adapted to receive gas under pressure that may be passed into the well from the surface of the ground and that discharges this gas under pressure into the oil string following each oil elevating stroke.

Another object of this invention is to provide an improved well pump that is double acting and that is operable to displace or elevate a charge of liquid during each movement of its plunger.

Another object of this invention is to provide an appliance or attachment for a well pump that renders the pump double acting thereby greatly increasing its efficiency.

Another object of this invention is to provide an appliance or attachment of the character mentioned that may be readily applied to a typical well pump with a minimum of alteration and at little cost.

Another object of this invention is to provide an attachment or appliance for a typical single acting deep well pump that makes the pump double acting and that provides for the alternate pumping of liquid and gas.

The various objects and features of my invention will be fully understood from the following detailed description of typical preferred forms and applications of my invention, throughout which description reference is made to the accompanying drawings, in which:

Fig. 1 is a central longitudinal detailed sectional view of one form of the invention showing the parts in the operative positions in the well. Fig. 2 is an enlarged fragmentary longitudinal detailed sectional view of the upper portion of the pump illustrated in Fig. 1 showing the plunger at the lower end of its stroke. Fig. 3 is a view similar to Fig. 1 illustrating another form of the invention. Fig. 4 is an enlarged, lon-

gitudinal, fragmentary detailed sectional view of the upper portion of the pump illustrated in Fig. 3 showing the plunger latched at the lower end of its stroke. Fig. 5 is a view similar to Fig. 1 illustrating still another form of the invention. Fig. 6 is an enlarged fragmentary longitudinal detailed sectional view of the upper portion of the pump illustrated in Fig. 6 showing the plunger at the lower end of its stroke, and Fig. 7 is an enlarged fragmentary longitudinal sectional view of a slightly modified form of anchor assembly.

The present invention is adapted to be embodied in various forms and may be provided in the form of attachments for use with typical well pumps. In the following detailed disclosure I will describe several typical forms and installations of the invention, it being understood that the invention is not to be construed as limited or restricted to the specific structures or applications about to be described, but that it is to be taken as including any features or modifications that may fall within the scope of the claims.

The embodiment of the present invention illustrated in Figs. 1 and 2 of the drawings includes, generally, a seat 10 on the lower end of an oil string S, a pump barrel 11, an anchor 12 connected with the barrel 11 and cooperating with the seat 10 to suspend the barrel where it extends beyond the lower end of the string S, a plunger 13 operable in the barrel 10 to displace liquid upwardly into the string S during its down stroke and means 14 whereby the plunger 13 displaces gas into the string S during its up stroke.

The seat 10 and the associated parts may be in the form of an attachment for application to the lower end of a typical oil string S. The string S is provided to conduct the fluid from the well and may be made up of lengths of tubing in the usual manner. The seat 10 is a tubular member connected with the lower end of the oil string S by a suitable coupling 15. A downwardly and inwardly inclined wall 16 is provided on the interior of the seat 10. An annular downwardly facing shoulder 17 is provided on the interior of the seat 10 below its inclined wall 16. The shoulder 17 is preferably inclined downwardly and outwardly as illustrated. In accordance with the invention a tubular section 18 is connected with the lower end of the seat 10. The section 18 may be threaded on the lower portion of the seat 10 and may be of substantially the same diameter as the oil string S. A shoe or collar 19 is provided on the lower end of the section 18 and presents an upwardly facing internal shoulder 20.

An annular or tubular packing assembly 21 is provided in the section 18 and is supported on the shoulder 20. The packing assembly 21 may comprise superimposed rings. Alternate rings 5 of the assembly 21 have inwardly and outwardly convergent ends and the ends of the adjacent rings cooperate whereby the packing assembly tends to expand both inwardly and outwardly when subjected to compression. The lower end of 10 the lowermost ring of the assembly 21 is inclined downwardly and inwardly and cooperates with the shoulder 20 which may be correspondingly inclined, as illustrated. A metal ring or follower 22 is provided at the upper end of the packing 15 assembly 21 and its upper end cooperates with a downwardly facing shoulder 23 on the interior of the section 18. The packing assembly 21 is adapted to be compressed by the collar 19 and is provided to seal between the section 18 and parts 20 on the barrel, as will be hereinafter described.

The barrel 11 constitutes the outer relatively stationary element of the pump proper. The barrel 11 is an elongate tubular structure extending downwardly from the packing assembly 21 to 25 project into the fluid of the well. A standing valve V is provided on the lower end of the barrel 11. The standing valve V may include a tubular cage 24 having an internal seat 25 and a ball 26 in the cage 24 for seating downwardly on 30 the seat 25. It will be observed that the lower end of the barrel 11 carrying the valve V may be unsupported and need not be provided with an anchor or the like. A connecting member 27 is threaded in the upper end of the barrel 11 to facilitate its connection with the anchor 12. The barrel 11, its valve V and the plunger 13 may be 35 typical well pump parts.

The anchor 12 is provided to suspend the barrel 11 and to hold the barrel against movement. 40 The anchor 12 includes a tubular member 28 threaded on the upper end of the connecting member 27 to extend upwardly through the packing assembly 21. The tubular member 28 extends upwardly into the lower end of the seat 10 and its upper portion may be increased in wall 45 thickness. A connecting member 29 is threaded in the upper end of the tubular member 28. An anchor collar 30 is threaded on the upper portion of the connecting member 29 and has its lower 50 end spaced some distance above the upper end of the tubular member 28. The anchor collar 30 is provided with a downwardly and inwardly inclined surface 31 adapted to cooperate with the wall 16 of the seat 10 to suspend the barrel 11 from the seat. The cooperation of the surface 31 with the seat wall 16 also prevents fluid from the 55 string S from passing downwardly into the tubular section 18.

A split lock ring 32 surrounds the connecting member 29 between the lower end of the anchor collar 30 and the upper end of the tubular member 28. The periphery of the lock ring 32 is tapered downwardly and inwardly. When the pump is lowered through the string S to its position in the well the tapered periphery of the lock ring 32 cooperates with the inclined wall 16 of the seat 10 and this cooperation causes contraction of the ring. When the ring 32 moves past the shoulder 17 it snaps outwardly or returns to its original dimensions to cooperate with the shoulder 17. The cooperation of the lock ring 32 with the shoulder 17 serves to hold the barrel 11 and its associated parts against upward movement relative to the string S. When an 70 upward strain is applied to the pump to remove 75

it from the well the cooperation of the upper outer corner of the lock ring 32 with the inclined shoulder 17 results in contraction of the ring so that it passes upwardly through the seat 10 allowing the pump to be withdrawn from the seat 10. 5 In accordance with the invention the anchor 12 is provided with means for packing about the plunger 13. A tubular section 33 is threaded in the upper end of the anchor collar 30 and projects 10 upwardly from the collar. A collar 34 is threaded on the upper end of the section 33 and carries a tubular member 35. A packing assembly 36 similar in nature to the packing assembly 21 is arranged within the tubular member 35. A gland or follower 37 is threaded in the upper end of the member 35 to compress the packing assembly 36. The upper end of the follower 37 may be open to the interior of the string S to allow the fluid pressure or fluid head in the string to compress the packing assembly 36. 15

The plunger 13 is the reciprocable element of the pump and is operable by a typical pump rod R. The plunger 13 extends through the packing assembly 36, and the various parts of the anchor 12 to extend into the barrel 11. The plunger 13 carries the cup leathers or other suitable sealing elements 38 for slidably sealing with the interior of the barrel 11. The sealing elements 38 are preferably such that they are effective during both strokes of the plunger. Heads 39 may be 20 provided on the plunger 13 at the opposite ends of the assembly of sealing elements 38. The reciprocating plunger 13 is tubular to conduct the liquid from the barrel 11 to the string S during its down stroke. A working valve V' is provided on the plunger 13 to control the passage of fluid through the plunger. In the particular instance illustrated the valve V' is provided at the upper end of the tubular plunger 13, it being understood that the valve V' may be otherwise positioned on the plunger 13. The valve V' includes a ported cage 40 secured to the upper end of the plunger 13 and to the lower end of the rod R to form a connection between the plunger and rod. The cage 40 houses a valve or ball 41 which cooperates with a seat in the cage to control communication between the interior of the string S and the interior of the barrel 11. The above described packing assembly 36 seals about the plunger 13 to prevent the leakage of fluid 35 from the string S into the anchor 12. 40

The means 14 provides for the pumping of gas from the well into the string S during each up stroke of the plunger 13. It is a feature of the invention that the means 14 renders the pump double acting so that it displaces or forces fluid into the string S during each movement of the plunger 14. The means 14 includes a multiplicity of ports 43 in the wall of the section 18. The ports 43 communicate with the interior of the section 18 between the lower end of the seat 10 and the upper end of the follower 22. In installations where the level L of the liquid in the well is above the ports 43 the invention provides a tube 44 for carrying the gas from the well to 60 the ports. The tube 44 may be threaded on the exterior of the collar 19 to have its lower end closed against the entrance of the liquid in the well. The tube 44 extends upwardly around the section 18, the seat 10 and the string S to a 65 point above the level L of the fluid in the well. The gas conducting tube 44 surrounds the parts just mentioned with substantial clearance leaving an annular passage for conducting the gas 70 downwardly to the ports 43. The tube 44 may be 75

formed of one or more lengths of tubing. It is to be understood that where the level L of the liquid in the well is below the ports 43 the tube 44 may be eliminated.

5 The means 14 further includes inlet valve means for controlling the admission of gas from the ports 43 and the interior of the section 18 to the upper end of the pump barrel 11. An annular inclined shoulder or seat 45 is provided 10 on the interior of the member 28 and ports 46 extend through the wall of the member 28 to the seat 45. The ports 46 have their outer ends in communication with the interior of the section 18 and, therefore, communicate with the 15 ports 43. A shiftable gas inlet valve 47 of tubular form is arranged within the member 28 to cooperate with the seat 45. The upper end of the valve 47 is tapered to effectively cooperate with the seat 45 and fully close the ports 46. The 20 valve 47 surrounds the plunger 13 with substantial clearance leaving an annular fluid passage. A spring 48 is arranged under compression between the upper end of the connecting member 27 and the lower end of the valve 47 to yieldingly 25 hold the valve in sealing cooperation with the seat 45 where it closes the ports 46. The plunger 13 extends through the connecting members 27 and 29, the tubular member 28 and the anchor collar 30 with substantial clearance leaving an 30 annular gas passage P. The lower end of the passage P is in direct communication with the upper end of the barrel 11 and the valve 47 described above controls the communication between the passage P and the interior of the 35 tubular section 18.

The means 14 further includes outlet valve means controlling communication between the upper end of the passage P and the lower end of the string S. An annular recess or groove 49 is provided in the interior of the anchor collar 30 to constitute the upper end of the passage P. A plurality of spaced vertical ports 50 extend downwardly through the collar 30 from its upper end and communicate with the groove 49. A shiftable discharge valve 51 is provided to control the ports 50. The valve 51 may be a tubular member shiftable surrounding the tubular section 33. The lower end of the valve 51 is adapted to cooperate with the upper end of the collar 30 to close the ports 50. Gravity and the hydrostatic head in the string S serve to hold the valve 51 in its closed position and to return it to its closed position after operation. The lower end of the collar 34 limits the upward travel of the valve 51.

55 When the oil string S is to be run into the well the seat 10, the tubular section 18, the collar 19, the tube 44 and the associated parts are connected with the lower end of the string. Following 60 the proper setting or positioning of the string S the well pump may be lowered through the string to its operative position. When the pump approaches its operative position the barrel 11 passes through the packing assembly 21. When the lock ring 32 engages the inclined seat surface 65 16 it is contracted and upon passing the shoulder 17 the lock ring 32 expands or returns to its normal size. The anchor surface 31 seats on the wall 16 of the seat 10 to suspend the barrel 11 from the seat while the ring 32 cooperates with the shoulder 17 to prevent upward movement of the inner barrel and the connected parts. The pump is in condition for operation when seated or located as just described.

70 During operation the string of pump rods R

is reciprocated in the usual manner to reciprocate the plunger 13. During the upstroke of the plunger 13 a reduced pressure is created in the lower end of the barrel 11 resulting in opening 5 of the valve 26 and passage of liquid from the well into the lower end of the barrel. As the plunger 13 moves upwardly gas which may have been drawn into the upper end of the barrel during the previous down stroke of the plunger is forced upwardly through the passage P under 10 pressure and raises the valve 51 to pass into the lower end of the oil string S. Thus during the up stroke of the plunger 13 a charge of liquid is drawn into the barrel 11 and a charge of gas is discharged into the lower end of the string S. 15 During the down stroke of the plunger 13 the charge of oil in the barrel 11 below the sealing elements 38 of the plunger 13 is displaced upwardly through the tubular plunger to open the valve 41 and discharge into the oil string S. As 20 the plunger 13 moves downwardly in the barrel 11 a reduced or lessened pressure is created in the barrel above the elements 38 and the gas in the well is drawn or received in the barrel above the plunger. Thus during the down stroke of 25 the plunger 13 a charge of liquid is discharged into the lower end of the oil string S and a charge of gas is received in the barrel 11 above the sealing elements 38. The gas received in the pump may be rock gas or gas produced from the earth 30 formation or may be gas pumped into the well from the surface of the ground to facilitate the recovery of the oil or liquid. The pump illustrated in Figs. 1 and 2 of the drawings operates to discharge alternate charges of liquid and gas 35 into the oil string S under pressure. The charges of gas forced into the oil string by the pump greatly assist in elevating or lifting the liquid to the surface of the ground in the well known manner. Being double acting the well pump described above is particularly efficient. It will be noted that the barrel 11, the plunger 13 and the valves V and V' may be elements of a typical well pump while the other parts described above may constitute an attachment or appliance for making the pump double acting and gas handling.

40 Figs. 3 and 4 of the drawings illustrate a form and application of the invention embodying a typical anchor 12^a and adapted to be anchored in the lower end of a string of oil tubing T. The pump illustrated in Figs. 3 and 4 of the drawings includes, generally, a pump barrel 11^a carrying the anchor 12^a and adapted to be anchored in the lower end of the string of oil tubing T, a plunger 13^a operable in the barrel 11^a, packing 45 means 55 carried by the barrel 11^a to seal with the string T, and means 14^a whereby the pump is operable to handle gas admitted to the string T below the packing means 55.

The barrel 11^a may be of typical construction, 50 being an elongate tubular member or assembly. The barrel 11^a extends longitudinally through the string T with substantial clearance leaving an annular fluid passage 56. A connecting member 57^a is provided on the upper end of the barrel 11^a to facilitate its connecting with the packing means 55. A typical anchor shoe 57 is provided on the lower end of the string T. The shoe 57 has a downwardly and inwardly inclined seat 58 on its interior and has an annular internal flange 59 spaced below the seat 58.

55 The anchor 12^a is provided on the lower end of the barrel 11^a to cooperate with the anchor shoe 57. In practice the anchor 12^a may be connected with the lower end of the barrel 11^a by 60

a tubular valve cage 60. The valve cage 60 may be threaded on the anchor 12^a and may be connected with the barrel 11^a by a suitable connecting member 61. The anchor 12^a has a downwardly and inwardly tapered face 62 adapted to seat on and seal with the seat 58. The lower portion of the anchor 12^a is split into a multiplicity of flexible fingers 63 which carry lugs 64. The lugs 64 are adapted to spring into cooperation with the under side of the flange 59 when the pump is lowered into place and their cooperation with the flange 59 releasably holds the pump against upward movement. The anchor shoe 57 and the anchor 12^a just described may be of typical construction. A standing valve is provided on the lower end of the barrel 11^a. The standing valve may comprise a seat 65 in the lower portion of the cage 60 and a ball valve 66 for cooperating downwardly with the seat 65. The connecting member 61 may have an internal perforate web 67 to limit the upward movement of the valve 66.

The plunger 13^a is the reciprocating element of the pump. The plunger 13^a extends into the barrel 11^a from its upper end and carries series of packing means or elements 68 for slidably sealing with the interior of the barrel 11^a. The sealing elements 68 are preferably operable to seal with the interior of the barrel 10^a when the plunger 13^a operates in both directions. The plunger 13^a is tubular to pass or conduct fluid from the barrel 11^a upwardly into the string T. A traveling valve is carried by the plunger 13^a. The traveling valve may be arranged at the upper end of the plunger 13^a and may comprise a cage 69 forming a connection between the upper end of the plunger 13^a and the plunger operating rod R. The cage 69 is perforate and houses a ball valve 70. The valve 70 is adapted to seat downwardly in the cage 69 to close off communication between the interior of the string T and the interior of the plunger 13^a during the upward movement of the plunger.

The packing means 55 is provided to seal off the upper end of the passage 56 from the interior of the string T above the passage. The packing means 55 includes a tubular section 71 threaded on the upper end of the connecting member 57^a to extend upwardly through the string of tubing. The upper portion of the section 71 is thickened and an annular external flange 72 is provided on the member 71 between its ends. A packing assembly 73 surrounds the thickened portion of the section 71 above the flange 72. The packing assembly 73 may be similar to the above described packing assembly 21 comprising a multiplicity of superimposed rings having tapered abutting ends whereby the assembly is expansible outwardly as well as inwardly when subjected to compression. The packing assembly 73 is operable to seal with the interior of the string T and with the exterior of the tubular section 71. A follower 74 is provided to cooperate with the upper end of the packing assembly 73. The follower 74 is an elongate tubular member and its lower end bears on the inclined upper end of the upper ring in the packing assembly 73. A tubular member 75 of reduced diameter is threaded in the upper end portion of the section 71 and a packing gland housing or body 76 is carried on the upper end of the member 75. A packing assembly 77 is arranged in the body 76 to seal about the plunger 13^a. The packing assembly 77 may be similar to the assembly 55. A follower 78 is threaded in the upper end of the body 76 to actuate or com-

press the assembly 77. A spring 79 is arranged under compression between a shoulder 80 on the body 76 and a shoulder 81 on the follower 74 to urge the follower downwardly against the packing assembly 73. The spring 79 is provided to actuate or assist in actuating the packing assembly 73.

The invention provides means for connecting the barrel 11^a and the parts connected therewith with the plunger 13^a and rod R to be run through the tubing string T on the rod R with the packing assembly 73 in a normal uncompressed state. The tubular follower 74 projects upwardly beyond the upper end of the gland body 76 and has two diametrically opposite bayonet slots 82. The bayonet slots 82 extend downwardly from the upper end of the tubular follower 74. A pin 83 projects radially from opposite points on the cage 69 to cooperate with the bayonet slots 82. When the follower 74 is connected with the rod R by the pin 83 cooperating with the bayonet slots 82, the barrel 11^a, the tubular section 71, the member 74, the gland body 76 and the associated parts are supported on the shoulder 81 through the medium of the spring 79. Thus the pressure exerted on the packing assembly 73 by the spring 79 is relieved from the packing assembly when the pump is run into the well. Following the anchoring of the pump in the shoe 57, as described above, the rod R may be given a partial rotation and a slight upward movement to disengage the pin 83 from the bayonet slots 82 whereupon the plunger 13^a may be reciprocated by the rod R.

The means 14^a is provided to render the pump double acting and capable of handling gas as well as liquid. The means 14^a includes means for admitting gas from the well or well casing into the passage 56. A multiplicity of spaced ports 84 is provided in the string of tubing T to communicate with the passage 56 below the flange 72. In certain installations the ports 84 may directly communicate with the portion of the well or the well casing carrying the gas. Where the level L of the liquid in the well is above the ports 84, as illustrated in the drawings, a tube 85 may be threaded on a coupling 86^a of the string T to extend upwardly around the string to a point above the liquid level L. The tubing 85 is spaced some distance from the string T to leave an annular passage placing the ports 84 in communication with the portion of the well containing the gas.

The means 14^a further includes inlet valve means for governing the admission of gas to the upper end of the barrel 11^a. This valve means may include a seat 86 on the interior of the tubular section 71. Ports 87 extend through the wall of the tubular section 71 to have their outer ends in communication with the passage 56 and to have their inner ends at the seat 86. A shiftable tubular valve 88 is arranged in the tubular section 71 and is adapted to seat upwardly against the seat 86 to close the ports 87. A spring 89 is arranged under compression between the lower end of the valve 88 and the upper end of the connecting member 57^a to urge the valve 88 to its closed position. The plunger 13^a extends through the tubular section 71 with substantial clearance leaving a fluid passage 90 which has communication with the interior of the barrel 11^a and which extends upwardly to an annular groove 91 in the upper portion of the section 71. Valve means is provided to govern communication between the passage 90 and the interior of the string T above the packing means 55. This valve means may

include a multiplicity of ports 92 extending upwardly through the section 71 from the groove 91 to the upper end of the section. A shiftable tubular valve 93 surrounds the member 75 and is adapted to cooperate with the upper end of the section 71 to close the ports 92. Gravity and the head of fluid in the tubing string T may hold the valve 93 in its closed position.

The pump illustrated in Figs. 3 and 4 of the drawings may be anchored in its operative position in the well by lowering it into the well on the string of rods R. When the pump is lowered through the well the pin 83 cooperates with the bayonet slots 82 whereby the rod R carries the tubular follower 74 and through the medium of the spring 79 bearing on the shoulder 81 carries the other parts of the pump. When the pump reaches its proper position in the well the anchor 12^a is automatically latched in the shoe 57, as described above. Following the anchoring of the pump the rod R is turned and moved upwardly to release the pin 83 from the bayonet slots 82. The spring 79 then exerts its pressure upon the packing assembly 73 to actuate the same against the control of the string T and the exterior of the section 71. The pump is then in condition for operation.

During the down stroke of the plunger 13^a fluid within the barrel 11^a below the packing elements 68 is displaced upwardly through the plunger 13^a to discharge past the valve 70 into the string T. As the plunger 13^a moves downwardly a reduced pressure is created in the upper portion of the barrel 11^a causing opening of the valve 88 and the admission of gas from the well above the level L. Thus the down stroke of the plunger 13^a results in the discharge of a charge of liquid into the string T and the reception of a charge of gas in the barrel 11^a above the sealing elements 68 of the plunger. As the plunger moves upwardly the gas above its sealing elements 68 is forced upwardly through the passage 90 and ports 92 to lift the valve 93 and flow into the string T. Upward movement of the plunger 13^a creates a reduced pressure in the lower portion of the barrel 11^a so that the valve 66 is unseated and liquid is drawn into the lower portion of the barrel. From the above it will be apparent that the pump illustrated in Figs. 3 and 4 of the drawings is a double acting pump operable to displace a charge of liquid into the string T during each down stroke of its plunger 13^a and operable to displace a charge of gas into the string T during each up stroke of its plunger. The charges of gas thus admitted to the tubing string T materially assist in raising or lifting the pumped liquid to the surface. The barrel 11^a with its anchor 12^a and the plunger 13^a with its valve 70 may be typical well pump parts and the packing means 55 and the means 14 may comprise an attachment to adapt the pump for the duty described above.

Figs. 5 and 6 of the drawings illustrate a form of the invention adapted to handle liquid or oil during each stroke of its plunger. In the pump illustrated in Figs. 5 and 6 the barrel 11^a, the plunger 13^a, the packing means 55 and the valves 88 and 93 may be identical with the corresponding elements of the form of the invention illustrated in Figs. 3 and 4 and corresponding reference numerals will be employed for such parts. The pump illustrated in Figs. 5 and 6 differs from the structure illustrated in Figs. 3 and 4 in that the tubing string T is imperforate throughout its length and the collar 86 and tube 85 are omit-

ted. The lower end of the passage 56, occurring between the barrel 11^a and the interior of the tubing string T has communication with the interior of the anchor 12^a below the valve 66. A plurality of lateral ports 96 is provided in the anchor 12^a to place the lower portion of the passage 56 in communication with the interior of the anchor. The ports 96 communicating with the interior of the anchor 12^a below the valve 66 admit the well fluid into the passage 56.

The operation of the pump illustrated in Figs. 5 and 6 of the drawings is substantially the same as the operation of the structure illustrated in Figs. 3 and 4, except that the pump handles liquid during each movement of its plunger 13^a. During the down stroke of the plunger 13^a liquid is displaced from the lower portion of the barrel 11^a through the plunger to discharge into the tubing string T. During the down stroke of the plunger 13^a liquid is drawn through the anchor 12^a, the ports 96, the passage 56 and the ports 87 into the upper portion of the barrel 11^a. During the up stroke of the barrel 11^a the liquid in the barrel above the sealing elements 68 is forced through the ports 92 and the tubular follower 74 into the tubing string T and liquid is drawn into the lower portion of the barrel 11^a through the anchor 12^a and past the valve 66.

Fig. 7 of the drawings illustrates a slight modification of the plunger and anchor structure illustrated in Figs. 5 and 6. In this form of the invention a member 98 is interposed between the upper end of the anchor 12^a and the lower end of the valve cage 60. The member 98 may be threaded on the upper end of the anchor 12^a and may be threaded into the lower end of the cage 60. A central longitudinal opening 99 extends through the member 98 to place the interior of the anchor 12^a in communication with the valve seat 100 of the standing valve 66. A plurality of lateral ports 101 is provided in the wall of the member 98 and places the opening 99 in communication with the passage 56. The ports 101 are adapted to admit fluid from the well into the passage 56 during the down stroke of the plunger 13^a. The member 98 may be readily interposed between the cage 60 and anchor 12^a of a typical well pump so that the pump may embody a typical standing valve and a typical anchor.

Having described only typical preferred forms and applications of my invention, I do not wish to be limited or restricted to the specific details herein set forth, but wish to reserve to myself any variations or modifications that may appear to those skilled in the art or fall within the scope of the following claims.

Having described my invention, I claim:

1. Well pumping apparatus including, a tubing for conducting the fluid to the surface, a barrel in the tubing having an inlet valve at its lower end, a tubular plunger reciprocable in the barrel and having a discharge communicating with the tubing, a traveling valve on the plunger, means sealing off between the barrel and tubing below the discharge of the plunger, there being communicating ports in the barrel and tubing below said means, an inlet valve controlling the port in the barrel, and outlet valve means controlling communication between the upper end of the barrel and the tubing above the sealing means.

2. In a double acting well pump for use in the well, a tubing for conducting the fluid to the surface, a barrel extending into the tubing and

- having an inlet valve for its lower end, a tubular plunger operable in the barrel and having a discharge communicating with the tubing, a working valve controlling the discharge from the plunger into the tubing, the plunger discharging into the tubing during its down stroke, means connecting the barrel with the tubing and sealing between the barrel and tubing below the discharge of the plunger, there being a port in the wall of the upper portion of the barrel, a tube on said means placing said port in communication with the well above its liquid level, a valve controlling said port and open during the down stroke of the plunger, and a valve governing communication between the upper end of the barrel and the tubing open during the up stroke of the plunger.
3. An attachment for a well pump for use on a tubing and having a barrel with a standing valve and a reciprocable tubular plunger having a working valve and operable in the barrel, said attachment comprising a tubular part secured to the upper end of the barrel and having a port in its wall, a tubular part secured to the tubing and surrounding the first tubular part to provide a space thereabout communicating with the port, there being a port in the second tubular part communicating with said space to admit fluid from the well to said space, a valve controlling the first mentioned port, and valve means governing communication between the upper portion of the barrel and the interior of the tubing.
4. In combination with a well pump including a tubing, a barrel with an inlet valve at its lower end and a tubular plunger operable in the barrel and having a discharge valve, an attachment for the pump comprising, a tubular member connected with the upper end of the pump barrel, a tubular extension on the lower end of the tubing, packing means sealing between the member and the interior of the tubing extension, there being ports in the member and tubing extension for placing the interior of the member and the upper end of the barrel in communication with the well, an inlet valve governing the admission of fluid to the barrel through said ports, and an outlet valve governing communication between the interior of the member and the tubing above the packing.
5. An attachment for a well pump for use on a tubing, said pump having a barrel with an inlet valve at its lower end and a tubular plunger operable in the barrel and having a discharge valve, the attachment comprising, a tubular member connected with the upper end of the barrel, packing means sealing between the member and the interior of the tubing, means for actuating the packing following the anchoring of the pump, there being ports in the member and tubing for placing the interior of the member and the upper end of the barrel in communication with the well, an inlet valve governing the admission of fluid to the barrel through said ports, and an outlet valve governing communication between the interior of the member and the tubing above the packing means.
6. An attachment for a well pump for use on a tubing, said pump having a barrel with an inlet valve at its lower end and a tubular plunger operable in the barrel and having a discharge valve, the attachment comprising, a tubular member connected with the upper end of the barrel and forming a fluid passage between the upper end of the barrel and the tubing, an outlet valve governing the passage of fluid through the member, means sealing between the exterior of the mem-

ber and the interior of the tubing, there being ports in the member and the tubing below the sealing means, and an inlet valve governing the admission of fluid from the well through the port in the member to the barrel.

7. An attachment for a well pump for use on a tubing, said pump having a barrel with an inlet valve at its lower end and a tubular plunger operable in the barrel and having a discharge valve, the attachment comprising, a tubular member connected with the upper end of the barrel and forming a fluid passage between the upper end of the barrel and the tubing, an outlet valve governing the passage of fluid through the member, means sealing between the exterior of the member and the interior of the tubing, there being ports in the member and the tubing below the sealing means, means placing the port in the tubing in communication with the well above the liquid level therein, and an inlet valve governing the admission of fluid from the well through the port in the member to the barrel.

8. An attachment for a well pump for use on a tubing, said pump having a barrel with an inlet valve at its lower end and a tubular plunger operable in the barrel and having a discharge valve, the attachment comprising, a tubular member connected with the upper end of the barrel and forming a fluid passage between the upper end of the barrel and the tubing, means on the member sealing about the plunger, an outlet valve governing the passage of fluid through the member, means sealing between the exterior of the member and the interior of the tubing, there being ports in the member and the tubing below the sealing means, and an outlet valve governing the admission of fluid from the well through the port in the member to the barrel.

9. A well pump for use on a string of tubing including, a seat connected in the tubing, there being a port in the wall of the tubing below the seat, a barrel extending from the lower end of the tubing, an anchor cooperating with the seat, a tubular member interposed between the barrel and the anchor whereby the anchor suspends the barrel, a plunger operable in the barrel, said member having a port in its wall, an inlet valve in the member controlling its port, and an outlet valve controlling the passage of fluid through the member from the barrel into the tubing.

10. A well pump for use on a string of tubing including, a seat connected in the tubing, there being a port in the wall of the tubing below the seat, means for maintaining said port in communication with the well above a liquid level in the well above said port, a barrel extending from the lower end of the tubing, an anchor cooperating with the seat, a tubular member interposed between the barrel and the anchor whereby the anchor suspends the barrel, a plunger operable in the barrel, said member having a port in its wall, an inlet valve in the member controlling its port, and an outlet valve controlling the passage of fluid through the member from the barrel into the tubing.

11. A double acting well pump for use on a string of tubing including, a seat connected in the tubing, there being a port in the wall of the tubing below the seat, a barrel extending from the lower end of the tubing, an anchor cooperating with the seat, a tubular member interposed between the barrel and the anchor whereby the anchor suspends the barrel, means packing between said member and the tubing, means maintaining said port in communication with the

well above a liquid level therein higher than said port to supply gas to said port, a plunger operable in the barrel, said member having a port in its wall, an inlet valve in the member controlling its port, and an outlet valve controlling the passage of fluid through the member from the barrel into the tubing.

12. A well pump for use with a tubing having a shoe and a port above the shoe, said pump including, a barrel in the tubing, an anchor on the barrel cooperating with the shoe to support the barrel on the tubing in spaced relation to its wall, a plunger operable in the barrel, a tubular member on the upper end of the barrel having a port in communication with the first mentioned port, means sealing said ports, an inlet valve governing the passage of fluid through said ports to the barrel, and an outlet port controlling the flow of fluid through said member from the barrel.

13. Well pumping equipment comprising a tubing for conducting the pumped fluid to the surface, a shoe on the tubing, the tubing having a port above the shoe, a barrel in the tubing, an anchor on the barrel cooperating with the shoe to support the barrel on the tubing in spaced relation to its wall, a plunger operable in the barrel, a tubular member on the upper end of the barrel having a port in communication with the first mentioned port, means sealing between the tubing and the member above said ports, means maintaining said ports in communication with the well above a liquid level higher than the port in the tubing to deliver gas to said ports, an inlet valve governing the passage of fluid through said ports to the barrel, and an outlet port controlling the flow of fluid through said member from the barrel.

14. Well pumping equipment comprising a tubing having a shoe, a barrel extending through the tubing with clearance, an anchor assembly on the barrel cooperating with the shoe to support the barrel, said assembly being ported to maintain the space between the barrel and tubing in communication with the well, a tubular plunger operable in the barrel, means sealing off the upper end of said space from the tubing above the barrel, means for compressing the sealing means, means maintaining the last mentioned means inoperative during movement of the pump through the well, the upper portion of the barrel being ported to communicate with the said space, valve means governing the admission of fluid to the upper portion of the barrel from said space, and valve means governing the passage of fluid from the upper end of the barrel to the tubing.

15. A double acting well pump comprising a tubing for conducting the pumped fluid, a barrel having an inlet valve for its lower end, means at the upper end of the barrel for locking the barrel to the tubing and releasable to allow upward withdrawal of the barrel from the well, a tubular plunger operable in the barrel and having a discharge communicating with the tubing, a working valve controlling the discharge from the plunger into the tubing, said means having ports for admitting fluid from the well to the upper portion of the barrel, inlet valve means controlling said ports, and discharge valve means governing communication between the tubing and the upper end of the barrel.

HERBERT A. SCHMIDT.
